UNITED STATES PATENT OFFICE.

EDWARD MELCHERS, OF TOLEDO, OHIO:

DESIGN FOR A SHOWER-BATH YOKE.

SPECIFICATION forming part of Design No. 32,225, dated February 13, 1900.

Application filed January 19, 1900. Serial No. 2,072. Term of patent 7 years.

To all whom it may concern:

Be it known that I, EDWARD MELCHERS, of Toledo, county of Lucas, and State of Ohio, have invented a certain new and useful Design for a Shower-Bath Yoke; and I do hereby declare that the following is a full, clear, and exact description of the invention, which will enable others skilled in the art to which it appertains to make and use the same; reference being had to the accompanying drawings, and to the figures of reference marked thereon, which form part of this specification.

My design has reference to a shower-bath yoke.

5 Figure 1 is a plan view of my shower-bath yoke. Fig. 2 is an elevation thereof.

As shown in the drawings, my design comprises a curved section to conform to the shape of the body about the shoulders, the ends of which are united, at which point there is a depending nipple.

Referring to the drawings, 1 is the curved section, the ends of which join at 2, the nipple 3 extending downwardly at this point. Section 1 is curved outwardly at 4 and 5 in the arc of a large circle and at 6 and 7 in the arc of a small circle. The portions 8 are curved inwardly, as shown. It will be observed that the general form of my shower-yoke is ellipsoidal, with contractions at the points 8. 25 30

Having described my invention, what I claim, and desire to secure by Letters Patent, is—

The design for a shower-bath yoke substantially as shown and described.

35 In testimony that I claim the foregoing as my own I affix my signature in presence of two witnesses.

EDWARD MELCHERS.

Witnesses:
